12 Claims. (Cl. 214—304)

1
This invention is concerned with improvements in the stripping or unwrapping of blasting explosive cartridges.

In the production of cartridges of gelatine, semi-gelatine and powdered explosives it is sometimes necessary to unwrap or strip cartridges from their wrappers and repack them, for example, in different sizes. Formerly, stripping has been achieved by an operator holding the cartridge, opening the ends by means of a pointed stick and thereafter unwinding the wrapper by pulling it clear which necessitates the use of both hands. The explosive portion is then put in a bin to be re-wrapped or re-worked and the wrapper put into another bin for subsequent destruction, for example, by controlled burning. This method of operation has many and varied disadvantages; thus the operator requires to handle the unwrapped explosive; the method is slow and cumbrous and does not allow the operator to develop a smooth rhythm such as would lead to high rates of throughput.

The object of the present invention is to provide a process which will facilitate the unwrapping or stripping of explosive cartridges, which can be carried out without necessitating the handling of unwrapped explosives by operators and which allows of a high rate of throughput.

I have now found that this object can be achieved by a process comprising passing a wrapped cartridge of a gelatine, semi-gelatine or powdered blasting explosive through an apparatus comprising a means for rotating said wrapped cartridge, means for simultaneously applying a gradually increasing pressure to its cylindrical surface until the ends of the wrapper unfold and the outer edge thereof has become free, and discharging means for delivering the partly unwrapped cartridge for instance to an operative for completion of the separation of the explosive from the wrapper.

According to the present invention the process for stripping blasting explosive cartridges of substantially cylindrical form comprises subjecting a cartridge while undergoing rotation to gradually increasing pressure applied to its cylindrical surface until the ends of the wrapper unfold and the outer longitudinal edge of the wrapper becomes free and forms a partially unrolled portion and then separating the explosive from its wrapper.

To separate the explosive from its wrapper an operative for instance can hold said unrolled portion in the hand and shake out the explosive.

Apparatus according to the invention comprises in combination a rotatable roller and a sta-

tionary plate, wherein the stationary plate forms with the roller an entry end and an exit end and a spacial distance decreasing gradually from the entry end to the exit end, wherein the roller has projections positioned thereon substantially parallel to the longitudinal axis, and wherein the stationary plate has projections parallel to those on the roller and on the side of the plate facing the roller.

10 The said apparatus preferably includes discharging means and means for adjusting the distance of the plate from the rotatable roller.

The stationary plate may have a plane surface facing the roller or may be concave with respect to the roller. The stationary plate may be a rigid sieve or a grid which is particularly desirable if the cartridges to be treated contain powdered explosives. Furthermore the stationary plate is preferably spring loaded.

20 The rotatable roller may be an endless belt of semirigid material.

For cartridges of normal size the diameter of the roller can be 8 inches and the projections of the roller may conveniently be $\frac{1}{16}$ inch. The roller should be capable of revolving at a rate of 20-40 and preferably about 30 revolutions per minute, and the narrowest distance apart between the rotatable roller and the stationary plate lies preferably between 1 inch and $\frac{1}{4}$ inch. A cartridge of $1\frac{7}{16}$ inches is found to require the maximum narrowest distance apart between the roller and the fixed plate of 1 inch and a cartridge of $\frac{5}{8}$ inch a narrowest distance apart of $\frac{5}{16}$ inch in order to effect the unfolding of the ends and the freeing of the outer longitudinal edge of its wrapper.

30 When using the apparatus the cartridge is fed in at the end of greatest clearance with its length approximately at right angles to the direction of travel and is positioned and gripped by the transverse bars or projections and then carried to the end of decreased clearance while being rotated and having a gradually increasing pressure applied to its cylindrical surface. At the end of the plate or grid the cartridge drops on a sheet which carries it to a tray from which the operative lifts it by the unrolled portion of the wrapping, shakes the explosive portion into a bin and deposits the waste wrapper in a further bin. By suitable positioning the operative can feed two cartridges simultaneously, one with each hand, and the apparatus can be controlled in such a way that while two cartridges are going through between the roll and the plate or grid the operator is shaking out the two preceding cartridges.

The invention is illustrated with reference to the diagrammatic drawing accompanying the specification which shows a sectional elevation of a preferred apparatus for carrying out the process of the invention for gelatine or semi-gelatine explosives. In the drawing, 1 is a rotatable roll of 8 inches diameter capable of rotating at 30 revolutions per minute and having longitudinal bars or projections 2 of $\frac{1}{16}$ inch height mounted thereon, 3 is a curved plate fitted with 10 similar longitudinal bars or projections 4, 5 is an arm supporting the plate 3, 6 is a sprung shaft supporting the ends of the arms 5, 7 is a guard supported by the bearing assembly 8, 9 is a hand wheel which operates an adjusting pin 10 through the nut 11 which is fixed to the frame 12. 13 is a spring to hold the plate 3 in position, 14 is a chute leading to the tray 15, and 16 is the feed opening of the apparatus. 3', 9' and 10' show alternative positionings of the curved plate 20 3, the hand wheel 9 and the adjusting pin 10.

In using this apparatus the clearance between the plate 3 and the roll 1 is first adjusted according to the diameter of cartridge in use by means of the adjusting pin 10. The adjustment is preferably such that the narrowest clearance is 1 inch for a cartridge of $1\frac{1}{16}$ inches and $\frac{1}{16}$ inch for a cartridge of $\frac{1}{8}$ inch. The cartridge is then fed in through the opening 16 with its length approximately parallel to that of the roll 1 which is rotated in an anti-clockwise direction. The cartridge is guided between the roll and the plate and is then carried along and rotated while an increasing pressure is applied to it so that by the time it falls over the end of the plate 3 on to the chute 14 which carries it to the tray 15 the ends of the wrapper of the cartridge unfold and the outer longitudinal edge of the wrapper becomes free and forms a partially unrolled portion. The operative then picks up the thus treated cartridge 40 by the unrolled portion of the wrapper, shakes the explosive portion out into a bin and deposits the wrapper in a further bin.

What I claim is:

1. A process for stripping blasting explosive 45 cartridges of substantially cylindrical form which comprises subjecting a cartridge while undergoing rotation to gradually increasing pressure applied to its cylindrical surface until the ends of the wrapper unfold and the outer longitudinal edge 50 of the wrapper becomes free and forms a partially

unrolled portion and then separating the explosive from its wrapper.

2. A process as claimed in claim 1 wherein the explosive is separated from its wrapper by holding said unrolled portion and shaking out the explosive.

3. Apparatus comprising in combination a rotatable roller and a stationary plate in which apparatus the stationary plate forms with the roller an entry end and an exit end and a spacial distance decreasing gradually from the entry end to the exit end, the roller has projections positioned thereon substantially parallel to its longitudinal axis, and the stationary plate has projections parallel to those on the roller and on the side of the plate facing the roller.

4. Apparatus as claimed in claim 3 which includes means for adjusting the distance of the plate from the rotatable roller.

5. Apparatus as claimed in claim 3 wherein the stationary plate has a plane surface facing the roller.

6. Apparatus as claimed in claim 3 wherein the stationary plate is concave with respect to the roller.

7. Apparatus as claimed in claim 3 wherein the stationary plate is a rigid sieve.

8. Apparatus as claimed in claim 3 wherein the stationary plate is a grid.

9. Apparatus as claimed in claim 3 wherein the rotatable roller is an endless belt of semi-rigid material.

10. Apparatus as claimed in claim 3 wherein the stationary plate is spring loaded.

11. Apparatus as claimed in claim 3 wherein the diameter of the roller is 8 inches, the projections of the roller are $\frac{1}{16}$ inch, the roller is adapted to revolve at a rate of 20-40 revolutions per minute, and the narrowest distance apart between the rotatable roller and the stationary plate lies between 1 inch and $\frac{1}{4}$ inch.

12. Apparatus as claimed in claim 3 which includes discharging means.

DUGALD MITCHELL.
